UNITED STATES PATENT OFFICE.

ERNEST A. LOWE, OF PLAINFIELD, NEW JERSEY, ASSIGNOR TO AUTOMATIC SPRINKLER COMPANY OF AMERICA, OF NEW YORK, N. Y., A CORPORATION OF NEW YORK.

AUTOMATIC FIRE-ALARM APPARATUS.

1,303,082.

Specification of Letters Patent.

Patented May 6, 1919.

Application filed March 10, 1916. Serial No. 33,242.

To all whom it may concern:

Be it known that I, ERNEST A. LOWE, a citizen of the United States, and resident of Plainfield, Union county, New Jersey, have 5 made a certain new and useful Invention Relating to Automatic Fire-Alarm Apparatus, of which the following is a specification, taken in connection with the accompanying drawing, which forms part of the 10 same.

This invention relates to fire alarm apparatus adapted to make an audible alarm signal when the temperature of the adjoining premises rises at an excessive rate and the 15 apparatus may comprise detent mechanism connected with a pneumatic thermostat detector having a restricted vent so as to release the detent mechanism on excessive rate of temperature rise. Preferably the weight 20 of the apparatus operates through suitable gearing a vibrator device coöperating with a signal diaphragm and horn, if desired, so that under emergency conditions the weight 25 of the apparatus descending through a number of feet can readily give a loud alarm signal without the necessity of relying on heavy operating springs or electric connections.

In the accompanying drawing showing 30 in a somewhat diagrammatic way illustrative embodiments of the invention,

Figure 1 is a sectional view taken substantially along the line 1—1 of Fig. 2.

Fig. 2 is a rear elevation, parts being 35 moved, taken substantially along the line 2—2 of Fig. 1.

Fig. 3 is a section taken along the line 3—3 of Fig. 1.

Fig. 4 is a detail elevation showing the 40 operating drum and connected detent devices; and

Fig. 5 is a top sectional view thereof.

A movable operating casing 42 containing 45 most of the parts of the mechanism and closed by the cover 53, may be formed of cast iron or other suitable material and may be provided with suitable curved lateral guides or runners 52 at either side of its rear portion so as to coöperate with the adjacent 50 wall and guide the descent of the device which may be suspended from a bolt or other support 54 by a ring 55 and connected suspending or driving cable 56. The apparatus may comprise a signal diaphragm 55 of metal or other suitable material 41 mount-

ed in any desirable way on the front of the casing, for instance, by securing over the edges of the same a suitable horn, such as 40, which may be of any convenient size and construction and may, if desired, be 60 so designed as to amplify or resonantly strengthen the alarm signal produced. A suitable contact member, such as 38, may be mounted on this signal diaphragm and may if desired be adjustably mounted as by 65 being formed on the end of the adjusting screw 39 extending through this diaphragm so as to be transversely adjusted with respect thereto and held in any desired position as by the lock nut indicated. A suitable vi- 70 brator device such as the toothed vibrator disk 37 may coöperate with this contact member so that when it is powerfully rotated it imparts a strong vibratory move- 75 ment to the diaphragm of sufficient frequency to produce a loud audible alarm signal.

Any suitable gearing may be used to rotate the vibrator preferably through the weight of the apparatus and if desired this 80 vibrator disk may be connected through any suitable gearing with a driving drum 22 over which the suspension driving cable 56 passes after passing over a guide such as 57, for instance. In this way the power 85 generated by the descent through a number of feet of the apparatus weighing some 10 to 20 pounds or more, may be utilized to give a loud alarm signal for a consider- 90 able time and at the same time avoid the un- certainty of spring or electric operation. The gearing may, if desired, be mounted in the connected frame plates 58 supported within the casing as by the legs or brackets 65 or bolted to the sides of the casing or 95 lugs formed thereon and this gearing may comprise a suitable winding ratchet device located in any part of the train of gearing and indicated for clearness of illustration as comprising the winding ratchet 35 on the 100 shaft 34 on which the vibrator disk is loosely mounted, the pawl 36 on this disk being normally yieldingly held in contact with this ratchet by the spring indicated. The pinion 33 on this shaft 34 may coöperate 105 with the intermediate gear 32 meshing in turn with the gear 30 on the shaft 31 carrying the driving pinion 29. An intermediate gear 28 meshes with this pinion and also meshes with the driving gear 27 operatively 110

connected to the driving drum 22. A lost motion impact starting device is preferably incorporated in this train of gearing so as to allow the preliminary movement of some 5 or all of the gearing as the apparatus descends after being released under emergency 10 conditions before the vibrator is rotated, so that the first motion of the vibrator has behind it considerable momentum or kinetic energy of these moving parts to effectively 15 prevent or minimize any sticking of the parts due to dirt, corrosion, etc. If desired, this lost motion impact starting device may be arranged in connection with the driving 20 drum and may as indicated in Figs. 1 and 4 comprise two lost motion parts such as the drive arm 24 secured to the drive shaft 25 on which the drive gear 27 is rigidly mounted, the outer end of this drive arm 24 25 operating with a drive slot 23 of sufficient extent to allow a comparatively free preliminary movement of the drum corresponding to a substantial descent of the released apparatus. If desired, a cushioning spring 30 25 may be arranged at the end of this slot 23 so as to somewhat cushion the contact between this drive arm and the end of the slot while still giving an increased impact starting impulse to the connected gearing 35 and vibrator. A relatively light take-up 40 spring 26 normally holds the drive arm in its normal inoperative position shown in Figs. 1 and 4, so that when the detent mechanism releases the drive drum this impact starting action can be effected.

Any suitable form of detent mechanism may be employed to release the driving devices under fire or other emergency conditions and if desired a suitable pivoted trigger or detent 20 may be mounted on the drive drum and normally held against its detent pin 63 by the detent spring 21. A latch 18 which may be pivotally mounted on the adjacent frame plate 58 may coöperate with this detent, the extent of engagement or overlap of these parts being considerably exaggerated in the drawing, and this latch may be controlled by its connected latch arm 17, the free end of which is normally held in set position by a catch such as 16, which as indicated in Figs. 1 and 3 may be pivoted about the pin 13 and have its extended catch arm 12 coöperate with the trip or release arm 11 which may be pivoted 45 about the pin 10 and have its upper end 9 actuated by a pneumatic or other thermostat detector device which is responsive to emergency fire conditions. As indicated in Figs. 2 and 3 the spring 15 may engage the 50 catch arm 12 so as to give it a self-releasing action and more effectively remove the connected catch 16 from the path of the latch arm. A similar releasing spring 66 may be connected to a projection on the latch such 55 as the resetting spring projection 19 con-

nected thereto so as to similarly exert a releasing action on this latch and quickly remove it from the path of the detent so that the drive drum can then freely rotate without engaging this coöperating detent 70 member.

It is desirable to provide suitable resetting devices to reset the parts of this detent mechanism when the apparatus is restored to its normal set position and the 75 drive mechanism rewound as by a key 51 coöperating as shown in Fig. 2 with the key shaft 50 connected with the drive shaft or other part of the gearing. For this purpose a resetter knob such as 43 may project from 80 the casing so that when manually raised it engages and lifts the resetter 44 which may be slidably mounted in a supporting yoke 45 on the frame plate 58. When this resetter is raised against the action of its return 85 spring 46 it carries upward the resilient arm 47 so as to bring it into engagement with the resetting spring projection 19 on the latch so as to bring this latch and its connected latch arm into the set position indicated in Fig. 4 in which the latch arm may 90 engage a stop such as 60 on the frame. And subsequently the further movement of the resetter made possible by the resilient character of the resetter arm and connected parts 95 or the lost motion which may be allowed to the latch arm carries the resetter rod 48 up into engagement with a resetter lug 49 which may be provided on the catch arm 16 so that this catch is then lifted in front of 100 the latch arm and the catch arm 12 is depressed so as to swing down out of the path of the trip 11 which is automatically restored to its set position as by the spring 14. A single upward movement of the resetting 105 device effects the resetting of all these parts of the detent mechanism in their proper order which is inverse to the order in which they automatically release under emergency conditions and then when the resetting device is released its return spring 46 retracts it to such extent as to carry it out of the path of the detent mechanism so that it cannot interfere with its emergency releasing action.

The trip may be actuated by a pneumatic 115 thermostat device comprising, for example, a light detector diaphragm 7 mounted in the casing 5 secured to the frame of the machine and having a connected pin or actuating device 8 which can be projected from the casing into engagement with the trip 9 so as to release the detent mechanism in the manner described. This thermostatic diaphragm may be actuated by the pressure generated 120 by heat expansion of air or other fluid in a suitable air chamber, such as 1, which may have the connecting air pipe 2 and coupling 3 transmitting this air pressure to the passage 6 formed in the diaphragm connection 4 so that this air pressure may be trans- 125 130

mitted to the small area chamber and exerted on the communicating face of the detector diaphragm. It is desirable for fire alarm service to provide a suitable pin hole 5 or small area vent communicating with the pneumatic system and if desired this vent 67 may be arranged on the air chamber 1 which may with advantage be mounted at the upper part of the apparatus where it can 10 be nearest to the ceiling and thus be influenced by the hotter air which collects near the ceiling under fire conditions. This vent 67 which may be screwed into the socket 68 in the air chamber may comprise a vent tube 15 69 preferably containing fibrous filtering material 70 and having a reduced inner end 71 so as to compensate for the normal temperature changes of a few degrees per minute which are caused by artificial heating 20 or other natural causes, while under the much more rapid rise of temperature caused by fire conditions the vent is insufficient to allow the escape of the expanding air which thus builds up pressure in the air chamber 25 and on the communicating detector diaphragm as to release the detent mechanism and effect the emergency operation of the alarm diaphragm as described.

This invention has been described in connection with a number of illustrative embodiments, forms, parts, materials, arrangements and constructions, to the details of which disclosure the invention is not of course to be limited, since what is claimed as 30 new and what is desired to be secured by Letters Patent is set forth in the appended claims.

1. In automatic fire alarm apparatus, a cast iron casing formed with curved lateral 40 guide runners on its rear portion to coöperate with a wall, a signal diaphragm and coöperating horn mounted in said casing, a contact member on said diaphragm, a toothed vibrator disk mounted in said casing 45 to coöperate with said contact member and vibrate said diaphragm to produce a loud alarm signal, a driving drum and a connected suspending driving cable normally suspending said casing and having a rotat- 50 ing influence on said driving drum, gearing comprising a winding ratchet device between said driving drum and said vibrator disk, said gearing comprising a lost motion impact starting device including a drive arm 55 coöoperating with a drive slot in said driving drum to have lost motion in connection therewith, a cushioning spring cushioning the emergency movement of such parts, a take-up spring normally holding said drive 60 arm in set position, detent mechanism releasably restraining the movement of said driving drum and comprising a detent on said drum and a coöperating pivoted latch, a resetting spring projection on said latch 65 and a releasing spring normally moving

said latch into release position, a latch arm connected to said latch, a catch coöperating with said latch arm and having a spring releasing device and a thermostatically controlled trip coöperating with said catch arm, 70 a resetting device coöperating with said detent mechanism and comprising a resetter having a resilient resetting arm coöperating with said resetting spring projection on said latch to reset the same and comprising a 75 resetter rod to subsequently engage and reset said catch and a vented pneumatic thermostat comprising a detector diaphragm to actuate said trip and comprising a connected air chamber mounted on the upper 80 portion of said casing.

2. In automatic fire alarm apparatus, a cast iron casing formed with curved lateral guide runners on its rear portion to coöperate with a wall, a signal diaphragm 85 mounted in said casing, a contact member on said diaphragm, a toothed vibrator disk mounted in said casing to coöperate with said contact member and vibrate said diaphragm to produce a loud alarm signal, a driving drum and a connected suspending driving cable normally suspending said casing and having a rotating influence on said driving drum, gearing comprising a winding ratchet device between said driving drum 90 and said vibrator disk, said gearing comprising a lost motion impact starting device, detent mechanism releasably restraining the movement of said driving drum and comprising a detent on said drum and a coöperating pivoted latch, a resetting spring projection on said latch and a releasing spring normally moving said latch into release position, a latch arm connected to said latch, a catch coöperating with said latch arm and having a spring releasing device and a thermostatically controlled trip coöperating with said catch arm, 100 a resetting device coöperating with said detent mechanism and comprising a resetter having a resilient resetting arm coöperating with said resetting spring projection on said latch to reset the same and comprising a resetter rod to subsequently engage and reset said catch and a vented pneumatic thermostat comprising a detector diaphragm to actuate said trip and comprising a connected air chamber mounted on the upper portion of said casing.

3. In automatic fire alarm apparatus, a 110 cast iron casing, a signal diaphragm mounted in said casing, a contact member on said diaphragm, a toothed vibrator disk mounted in said casing to coöperate with said contact member and vibrate said diaphragm to produce a loud alarm signal, a driving drum and a connected suspending driving cable normally suspending said casing and having a rotating influence on said driving drum, gearing comprising a winding ratchet de-

1
vice between said driving drum and said vibrator disk, said gearing comprising a lost motion impact starting device, detent mechanism releasably restraining the movement of 5 said driving drum, a resetting device co-operating with said detent mechanism and a vented pneumatic thermostat comprising a detector diaphragm to actuate said detent mechanism and comprising a connected air chamber mounted on the upper portion of 10 said casing.

4. In automatic fire alarm apparatus, a casing formed with guide runners on its rear portion to coöperate with a wall, a signal diaphragm mounted in said casing, a toothed vibrator disk mounted in said casing to co-operate with said diaphragm and produce a loud alarm signal, a driving drum and a connected weight operated driving cable normally suspending said casing and having a 15 rotating influence on said driving drum, gearing between said driving drum and said vibrator disk, said gearing comprising a lost motion impact starting device including a 20 cushioning spring cushioning its emergency movement, detent mechanism releasably restraining the movement of said driving drum and comprising a detent on said drum and a coöperating pivoted latch, a latch arm connected to said latch, a catch coöperating with said latch arm and having a spring 25 releasing device and a thermostatically controlled trip coöperating with said catch arm, a resetting device coöperating with said detent mechanism and comprising a resetter 30 having a resilient resetting arm coöperating with said latch to reset the same and comprising a resetter rod to subsequently engage and reset said catch and a vented pneumatic 35 thermostat to release said detent mechanism and comprising a connected air chamber mounted on the upper portion of said casing.

5. In automatic fire alarm apparatus, a casing, a signal diaphragm mounted in said 40 casing, a toothed vibrator disk mounted in said casing to coöperate with said diaphragm and produce a loud alarm signal, a driving drum and a connected weight operated driving cable having a rotating influence on 45 said driving drum, gearing between said driving drum and said vibrator disk, said gearing comprising a lost motion impact starting device including a cushioning spring cushioning its emergency movement, detent mechanism releasably restraining the movement of said driving drum and comprising a detent on said drum and a coöperating pivoted latch, a latch arm connected to said latch, a catch coöperating with said 50 latch arm and having a spring releasing device and a thermostatically controlled trip coöperating with said catch arm, and a vented pneumatic thermostat to release said 55 detent mechanism and comprising a connected air chamber.

6. In automatic fire alarm apparatus, a casing, a signal diaphragm mounted in said casing, a vibrator disk mounted in said casing to coöperate with said diaphragm and produce a loud alarm signal, a driving drum and a connected weight operated driving cable having a rotating influence on said driving drum, gearing between said driving drum and said vibrator disk, said gearing comprising a lost motion impact starting device allowing free initial rotation of said driving drum before said gearing is rotated, detent mechanism releasably restraining the movement of said driving drum and a thermostat to release said detent mechanism and comprising a connected air chamber.

7. In automatic alarm apparatus, a cast iron casing formed with curved lateral guide runners on its rear portion to coöperate with a wall, a signal diaphragm and coöperating horn mounted in said casing, a toothed disk vibrator mounted in said casing to vibrate said diaphragm to produce a loud alarm signal, a driving drum and connected suspending driving cable normally suspending said casing and tending to rotate said driving drum, gearing between said driving drum and said vibrator, said gearing comprising a lost motion impact starting device including a cushioning spring cushioning its emergency movement, detent mechanism releasably restraining the movement of said driving drum, a resetting device coöperating with said detent mechanism and an automatic detector device to release said detent mechanism and comprising an air chamber mounted on the upper portion of said casing.

8. In automatic alarm apparatus, a casing formed with guide runners on its rear portion to coöperate with a wall, a signal diaphragm and coöperating horn mounted in said casing, a toothed disk vibrator mounted in said casing to vibrate said diaphragm to produce a loud alarm signal, a driving drum and connected suspending driving cable normally suspending said casing and tending to rotate said driving drum, gearing between said driving drum and said vibrator, said gearing comprising a lost motion impact, starting device, including a cushioning spring cushioning its emergency movement, detent mechanism releasably restraining the movement of said driving drum, a resetting device coöperating with said detent mechanism and an automatic detector device to release said detent mechanism mounted on the upper portion of said casing.

9. In automatic alarm apparatus, a casing formed with guide runners on its rear portion to coöperate with a wall, a signal diaphragm and coöperating horn mounted in said casing, a vibrator mounted in said

- casing to vibrate said diaphragm to produce a loud alarm signal, a driving drum and connected suspending driving cable normally suspending said casing and tending to 5 rotate said driving drum, gearing between said driving drum and said vibrator, said gearing comprising a lost motion impact starting device, including a cushioning spring cushioning its emergency movement, detent mechanism 10 releasing restraining the movement of said driving drum, and an automatic detector device to release said detent mechanism.
10. In automatic alarm apparatus, a casing formed with guide runners on its rear portion to coöperate with a wall, a signal diaphragm and coöperating horn mounted in said casing, a vibrator mounted in said casing to vibrate said diaphragm to produce a loud 15 alarm signal, a driving drum and connected suspending driving cable normally suspending said casing and tending to rotate said driving drum, gearing between said driving drum and said vibrator, said gearing comprising a lost motion impact starting device, detent mechanism 20 releasing restraining the movement of said driving drum, and an automatic detector device to release said detent mechanism.
- 30 11. In automatic alarm apparatus, a casing, a signal diaphragm and coöperating horn mounted in said casing, a vibrator mounted in said casing to vibrate said diaphragm to produce a loud alarm signal, a driving drum and connected suspending driving cable normally suspending said casing and tending to rotate said driving drum, gearing between said driving drum and said vibrator, detent mechanism 35 releasing restraining the movement of said driving drum, and an automatic detector device to release said detent mechanism.
- 40 12. In automatic fire alarm apparatus, a casing formed with curved lateral guide runners on its rear portion to coöperate with a wall, a mechanically operating audible signal device mounted in said casing, a driving drum and connected weight operated driving cable normally suspending said casing and 45 tending to rotate said driving drum, gearing comprising a winding ratchet device between said driving drum and said signal device, said gearing comprising a lost motion impact starting device including a drive arm 50 coöperating with a drive slot in said driving drum to have lost motion in connection therewith, a cushioning spring cushioning the emergency movement of such parts, de-
- tent mechanism releasably restraining the movement of said driving drum, a resetting device coöperating with said detent mechanism and a vented pneumatic thermostat to release said detent mechanism and comprising an air chamber mounted on the upper portion of said casing. 55
13. In automatic fire alarm apparatus, a casing, a mechanically operating audible signal device mounted in said casing, a driving drum and connected weight operated driving cable, gearing between said driving drum and said signal device, said gearing comprising a lost motion impact starting device including a drive arm coöperating with a drive slot in said driving drum to have lost motion in connection therewith, a cushioning spring cushioning the emergency movement of such parts, detent mechanism 60 releasing restraining the movement of said driving drum, a resetting device coöperating with said detent mechanism and a vented pneumatic thermostat to release said detent mechanism and comprising an air chamber mounted on the upper portion of said casing. 65
14. In automatic fire alarm apparatus, a casing, a mechanically operating audible signal device mounted in said casing, a driving drum and connected weight operated driving cable, gearing between said driving drum and said signal device, said gearing comprising a lost motion impact starting device, detent mechanism 70 releasing restraining the movement of said driving drum, a resetting device coöperating with said detent mechanism and a vented pneumatic thermostat to release said detent mechanism and comprising an air chamber mounted on the upper portion of said casing. 75
15. In automatic fire alarm apparatus, a casing, a mechanically operating audible signal device mounted in said casing, a driving drum and connected weight operated driving cable, gearing between said driving drum and said signal device, said gearing comprising a lost motion impact starting device, detent mechanism 80 releasing restraining the movement of said driving drum, a resetting device coöperating with said detent mechanism and a vented pneumatic thermostat to release said detent mechanism and comprising an air chamber mounted on the upper portion of said casing. 85
16. In automatic fire alarm apparatus, a casing, a mechanically operating audible signal device mounted in said casing, a driving drum and connected weight operated driving cable, gearing between said driving drum and said signal device, said gearing comprising a lost motion impact starting device, detent mechanism 90 releasing restraining the movement of said driving drum, a resetting device coöperating with said detent mechanism and a vented pneumatic thermostat to release said detent mechanism and comprising an air chamber mounted on the upper portion of said casing. 95
17. In automatic fire alarm apparatus, a casing, a mechanically operating audible signal device mounted in said casing, a driving drum and connected weight operated driving cable, gearing between said driving drum and said signal device, said gearing comprising a lost motion impact starting device, detent mechanism 100 releasing restraining the movement of said driving drum, a resetting device coöperating with said detent mechanism and a vented pneumatic thermostat to release said detent mechanism and comprising an air chamber mounted on the upper portion of said casing. 105
18. In automatic fire alarm apparatus, a casing, a mechanically operating audible signal device mounted in said casing, a driving drum and connected weight operated driving cable, gearing between said driving drum and said signal device, said gearing comprising a lost motion impact starting device, detent mechanism 110 releasing restraining the movement of said driving drum, and a thermostat to release said detent mechanism and comprising an air chamber mounted on said casing. 115
